W. E. SODERBERG.
SNARE DRUM.
FILED MAR. 28, 1922.

Inventor

Walter E. Soderberg,
Sho. St. Louis.

Attorney

UNITED STATES PATENT OFFICE.

WALTER E. SODERBERG, OF DULUTH, MINNESOTA.

SNARE DRUM.

Application filed March 28, 1922. Serial No. 547,421.

To all whom it may concern:

Be it known that I, WALTER E. SODERBERG, a citizen of the United States, residing at Duluth, in the county of St. Louis and State 5 of Minnesota, have invented certain new and useful Improvements in Snare Drums, of which the following is a specification, reference being had therein to the accompanying drawing.

10 This invention relates to snare attachments for drums the principal object of which is to provide an improved form of such device having the advantages of improvements in adjustability as well as improvements in resultant sound.

15 Another object is to produce such a snare attachment having means for quickly and conveniently muffling the sound of the attachment when desired.

20 Other objects and advantages will appear in the further description of the invention.

Referring to the accompanying drawing forming part of this application in which like reference characters indicate like parts:

25 Figure 1 is a top plan view of a fragmental portion of a drum head having my improved snare attachment applied thereto;

Figure 2 is a side elevation of Figure 1 partly in section;

30 Figure 3 is transverse section on the line 3—3, Figure 2; and

Figure 4 is an extreme end elevation of the snare attachment.

1 represents the body portion of a drum 35 and 2 the lower head thereof which may be of any common snare drum construction and my improved snare attachment comprises the two outwardly projecting brackets 3 and 4 which are securely fastened in any desired

40 manner to the exterior of the opposite walls of the body portion 1 of the drum. In the outer extremities of each of the brackets 3 and 4 are mounted two spaced screw threaded adjusting and supporting bolts 5, each

45 pair of which carry upon the upper ends or heads thereof a U-shaped member 6 which is vertically slotted as at 7 in its upturned ends, resulting in a bifurcated portion at either end thereof, the termini of which are

50 turned outwardly at right angles as at 8 for a short distance only to form a keeper to

prevent dislodgment of the shafts or bridge trunnions 9, one of which is supported within each member 6; the shafts being held in position by means of common nuts 10 on either end thereof beneath the laterally turned projections 8.

11 represents the snare bridge which may be of any desired shape, though preferably tapered and trussed from the centermost portion thereof to the two ends, where it is forked as at 12, the ends of the forked portions being carried upon the trunnions 9 within the members 6. The bridge 11, thus supported, spans the head of the drum and is 65 spaced therefrom as clearly seen in Figure 2 of the drawings.

Upon the trunnions 9 intermediate of the ends of each fork 12 are loosely mounted a plurality of sheaves 13, fitting closely 70 against each other and filling the entire space intermediate of the ends of the tines of the forks. Intermediate of the tines of each fork and inwardly in respect to the sheaves 13 slightly above same, is supported 75 a cross-head, the transverse bar of which is indicated at 14 and the fork at 15. This cross-head is supported upon an externally screw threaded bolt 16 which is screw threaded within a boss like enlargement 37 80 just below the juncture of each fork 12 with the bridge. Inwardly of the fork 15 and outside of the cross-bar 14 occurs the head 17 of the rod 16, said head having holes therein as indicated at 18 whereby a pin 85 wrench may be applied and the head turned for adjustment of the cross head in or out, as is obvious. The cross bar 14 is made to extend at either end slightly beyond the inner walls of the tines of the fork 12 so 90 that the cross head is guided thereby and prevented from turning either one way or the other by the adjustment of the screw 16. Intermediate of the tines of each fork 15 is mounted a shaft 19 carrying a plurality 95 of sheaves 20 similar to the sheaves 13 and about these groups of sheaves at either end of the attachment the snare string 21 is reeved, one end of which is securely attached as at 22 in one of the adjustable 100 cross heads, and is passed outwardly over one of the sheaves 13 to and over the head

of the drum around one of the sheaves 13 at the opposite end of the attachment, to and around one of the sheaves 20, back again and around another sheave 13 in the same 5 end of the attachment, to and across the drum again, under and around another of the sheaves 13 in the other end of the attachment, etcetera, until all of the sheaves are utilized in the complete reeving of the 10 string when the other end is finally attached as at 23, opposite the end 22, and in the same cross head.

When the snare is thus strung or reeved it is obvious that a tightening of either or 15 both cross-heads will correspondingly tighten the snare string and the vibratory effect thereof will be thus governed as desired, and result in equal tension throughout the string transverse the head of the drum.

20 On the bracket 4 I have illustrated a horizontally elongated enlargement or boss 24 in which is pivotally mounted, upon the shaft 25, the muffler cradle 26, it having a transverse bed member 27 which engages 25 and carries upwardly the strands of the snare string 21 when the cradle is turned to its uppermost position as illustrated in dotted lines in Figure 2. In this manner it is apparent that the strings may be raised 30 from vibratory coaction with the head of the drum and the effect of the snare thus muffled, whereas when the muffler cradle is in its lowermost position as shown in Figure 2 it is out of action reclining upon the bracket 35 4 and held there by means of a suitable resilient clip or spring 28.

From the foregoing it is evident that I have devised a simple, efficient and practical 40 snare attachment for drums which is of pleasing appearance and has means for ready and convenient adjustment as to the normal relation of the snare strings to the head of the drum by adjustment of the nuts 30 upon the screws 5, and one having a convenient 45 and simple muffler attachment cooperatively

associated therewith, the advantages of which to a musician are obvious.

Having thus described my invention, what I claim and desire to secure by Letters Patents, is:

1. A snare for drums comprising laterally projecting brackets attached to the sides of the drum adjacent one end thereof, a bridge spanning the head of the drum and supported upon the brackets, a plurality of 55 strands of snare strings passing over the head of the drum and supported at the ends of the bridge, means at the ends of the bridge for automatically maintaining an equal tension upon all of the strands of the 60 snare string, means for adjusting said automatic equalizing means, and means at either end for raising and lowering the strands of the string bodily in respect to the head of the drum. 65

2. A snare for drums comprising laterally projecting brackets attached to the sides of the drum adjacent one end thereof, a bridge spanning the head of the drum and supported upon the brackets, a plurality of 70 strands of snare strings passing over the head of the drum and supported at the ends of the bridge, means at the ends of the bridge for automatically maintaining an equal tension upon all of the strands of the 75 snare string, means for adjusting said automatic equalizing means, means at either end for raising and lowering the strands of the string bodily in respect to the head of the drum, and muffling means carried by 80 one of the brackets for raising or lowering one end of all of the strands of the string simultaneously. 85

In testimony whereof I hereunto affix my signature in the presence of two witnesses.

WALTER E. SODERBERG.
